Primary Examiner — Lauren R Calve(74) *Attorney, Agent, or Firm* — JoAnn M. Seaton;
Griffiths & Seaton PLLC(57) **CLAIM**

The ornamental design for a hanger, as shown and described.

DESCRIPTION

FIG. 1 is a front, top perspective view of a hanger showing our new design;

FIG. 2 is a rear, bottom perspective view thereof;

FIG. 3 is a front view thereof;

FIG. 4 is a rear view thereof;

FIG. 5 is a right side view thereof;

FIG. 6 is a left side view thereof

FIG. 7 is a left side view thereof with obstructive unclaimed subject matter removed for clarity;

FIG. 8 is a top view thereof; and,

FIG. 9 is a bottom view thereof.

The features shown in broken lines are portions of the hanger forming no part of the claimed design.
